(57) CLAIM

I claim the ornamental design for a surgical saw blade hub with tangs, as shown.

DESCRIPTION

FIG. 1 is a top plan view (the bottom plan view being a mirror image) of a surgical saw blade hub with tangs; FIG. 2 is a side elevational view of the surgical saw blade hub with tangs;

FIG. 3 is a front elevational view of the surgical saw blade hub with tangs; and,

FIG. 4 is a top perspective view of the surgical saw blade hub with tangs.

The broken line showing is for illustrative purposes only and forms no part of the claimed design.
